UNITED STATES PATENT OFFICE.

OTTO FOLLENDER, OF EAST ISLIP, NEW YORK.

DESIGN FOR A DOLL-WIG.

58,900.

Specification for Design.

Patented Sept. 6, 1921.

Application filed November 19, 1920. Serial No. 425,285. Term of patent 3½ years.

To all whom it may concern:

Be it known that I, OTTO FOLLENDER, a citizen of Austria, residing at East Islip, Suffolk county, State of New York, have invented a new, original, and ornamental Design for a Doll-Wig, of which the following is a specification, reference being had to the accompanying drawing, forming a part hereof, which illustrates a perspective view of a doll-wig embodying my new design.

I claim:

The ornamental design for a doll-wig, as shown.

Signed at New York city, N. Y., this 17th day of Nov., 1920.

OTTO FOLLENDER.
